UNITED STATES PATENT OFFICE.

EWALD F. HEISER, OF DENVER, COLORADO.

HARNESS TRACE.

Application filed October 14, 1924. Serial No. 743,518.

To all whom it may concern:

Be it known that I, EWALD F. HEISER, a citizen of the United States, residing at Denver, the city and county of Denver and State of Colorado, have invented certain new and useful Improvements in Harness Traces; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to improvements in harness and has reference more particularly to improvements in the construction of the trace and the means for connecting the same to the hames.

20 The traces of a harness are almost invariably connected to the hames by means which permit relative movement. In some cases interconnected staples are used and in other cases the traces are provided at their 25 ends with loops for the reception of a pintle, by means of which the trace is pivotally connected to the hame. Where a loop and pintle are employed, the inside of the loop must be lined with metal, such as steel or iron, for 30 the purpose of resisting the wear, otherwise the material of the trace would soon wear through and the trace break.

One object of this invention is to produce 35 a trace construction that shall be sufficiently strong to withstand the severest strains to which the trace can reasonably be expected to be put, and which shall be so reinforced with metal that it will not readily wear out.

The above objects are attained by means 40 of a construction which will be hereinafter described in detail, reference for this purpose being had to the accompanying drawing in which the preferred embodiment thereof is illustrated, and in which:

45 Fig. 1 is a side elevation showing the front end of a trace and the manner in which it is attached to the hame;

Fig. 2 is a section taken on line 2—2, Fig. 1;

50 Fig. 3 is a perspective view of a metal lining for the opening in the end of the trace; and

Fig. 4 is a section similar to that shown in Fig. 2, showing a modified construction.

55 The trace in its preferred form consists of an assembly designated as a whole by letter

A, to which the leather strips B, C and D are secured in the manner hereinafter described.

The assembly A consists of two pieces of leather E and F and a metal eyelet or lining member G whose construction is clearly shown in Fig. 3. This eyelet or lining member has a central cylindrical portion H and substantially parallel radially projecting ends I and J of unequal length. In the drawing J is shown as being the longer. Ends I and J have registering openings K for the reception of the rivet L, while the end J has another opening M for the reception of a rivet N. One end of the strap E extends in between the ends I and J while the corresponding end of the strap F is wrapped about the cylindrical portion H and terminates at O. The straps E and F are stitched along their edges in the manner indicated by P in Fig. 1. The trace proper, consisting of straps B, C and D, is secured to the assembly A in the manner shown in Fig. 2. The strap C is tapered and overlaps the end of the assembly A, terminating at Q. The strap B extends forwardly to point R, while strap D is wrapped about the end of assembly A and terminates at S. Rivets L and T and seams U hold the straps together along the edges.

In Fig. 4 I have shown a trace having an assembly corresponding to assembly A just described, but differing therefrom in this, that the ends I and J are not separated by the leather strap E, but are in contact. The end J is offset and projects through an opening in the strap F, which passes around the cylindrical portion H and is held in place by the rivet N. The strap E lies on the outside of the end of strap F. This assembly is incorporated into the trace in the manner described in connection with Fig. 2.

The metal lining member, which serves as a wear clip, has another important function, which will be appreciated by those who are versed in this art. As ordinarily constructed, the trace is merely provided with a loop in the front end, which must be opened before the hame roller or pintle can be inserted. This makes it necessary to employ a tool having a tapering end, which tool is driven into the loop for the purpose of opening the same. This requires time and labor and often injures the trace. When the trace is made in accordance with

my invention, the wear clip is built into the trace and provides a cylindrical opening for the hame roller or pintle and thereby saves both time and labor in assembling the harness.

From the above description, it is apparent that I have produced a trace which has exceptional strength, which is protected against wear and which can be readily constructed.

Having now described my invention, what I claim as new is:

1. A trace composed of a number of separate strips of leather, a loop formed on the end of said trace composed of a plurality of said strips, a metal lining within said loop, said lining consisting of a metal plate having a cylindrical portion intermediate its ends disposed within the loop, the ends 20 of said lining being of unequal length and extending substantially radially from the

cylindrical portion, one of the strips forming the trace being disposed between the ends of the lining member, and means for fastening the lining member and the strips forming the trace in assembled relation. 25

2. A trace whose end portion comprises an inner assembly comprising a metal plate having a cylindrical portion intermediate its ends, the ends of said plate being disposed radially of the cylindrical portion, a strip of leather extended around the cylindrical portion and attached at its ends to said first mentioned strip, and an outer assembly comprising a strip having its end portion terminating adjacent the cylindrical portion, and a second strip having its end portion extended around the inner assembly and overlapping the end of the other strip forming the outer assembly. 30 35 40

In testimony whereof I affix my signature.

EWALD F. HEISER.
